UNITED STATES PATENT OFFICE.

OWEN J. McGANN, OF CARROLLTON, OHIO.

AUTOMATIC LUBRICATING SYSTEM FOR INTERNAL-COMBUSTION-ENGINE PISTONS.

1,347,959.

Specification of Letters Patent. Patented July 27, 1920.

Application filed May 31, 1919. Serial No. 301,074.

To all whom it may concern:

Be it known that I, OWEN J. McGANN, a citizen of the United States, residing at Carrollton, in the county of Carroll and 5 State of Ohio, have invented certain new and useful Improvements in Automatic Lubricating Systems for Internal-Combustion-Engine Pistons; and I do hereby declare the following to be a full, clear, and 10 exact description of the invention, such as will enable others skilled in the art to which it appertains to make and use the same.

This invention relates to an automatic lubricating system for internal combustion 15 engine pistons.

An object of the invention resides in the provision of a device by means of which oil will be fed directly between the piston and the wall of the cylinder, periodically.

20 A further object of the invention resides in the provision of means whereby the heat of the explosion in the combustion chamber will be prevented from destroying the oil between the piston and cylinder wall.

25 With these and other objects in view, such as will appear as my description progresses, my invention resides in the combination and arrangement of parts as set forth in and falling within the scope of the appended 30 claims.

In the drawing:

Figure 1 is a sectional view of my device illustrating the relation of the same to the cylinder and piston; and

35 Fig. 2 is a transverse sectional view on line 2-2 of Fig. 1.

The cylinder 1 is of the usual form, and a piston 2 is operable within the cylinder. This piston is provided on its upper face 40 with a non-heat conducting material which is in the form of a plate 2'. This plate is maintained in place on the upper face of the piston by a suitable metallic plate 3 which is secured by fasteners 4. The purpose 45 of this arrangement of the plate 2' will appear as the description progresses. The piston is also provided, substantially midway between its ends, with a cam-slot 5 in one side thereof, with which slot a peripheral groove 6 communicates.

The oiling device *per se* comprises a casting which includes a body portion 7 having screw threads 8 on one end thereof by means of which it may be attached to the cylinder 55 wall so that the oil supply duct will have communication with the interior of the

cylinder. This casting is also provided with a flange 10 between which and the wall of the cylinder a casting 11 is disposed so as to make the joint fluid tight. An opening 12 extends through the casting 7 and communicates with the interior of the cylinder at 13. This opening is circular in cross section, as illustrated in Fig. 2 of the drawing and in it a valve rod 14 is longitudinally 60 slidable. This valve rod is, for a portion of its length, circular in cross section and for the remainder of its length it is triangular in cross section as at 15, so that spaces 16 exist between the faces of the rod 14 and the wall of the opening. The longitudinal 65 opening 12 is adapted to be closed at the cylinder end by a valve 17, which is carried by the end of the rod 14 and beyond which a cam 18 extends. This rod 14 is normally 70 urged toward the piston, so that the normal tendency will be to open the valve 17, by a coil spring 18 which encircles the end of the rod 14 and bears at one end against a collar 19 on the rod and at the other end 75 against the face of the cap 20 which is in screw-threaded engagement with the end of the body portion 7 of the casting. The spaces 16 are supplied with oil through an oil duct 21 which is itself supplied by a 80 pipe 22 from a suitable oil supply. The cam slot 5 in the piston is aligned with the cam 18 on the rod 14, so that during the travel of the piston the cam will be projected into the cam slot by the action of the 85 spring 18.

In operation, as the piston reciprocates, each time the cam slot 5 passes the cam 18, the cam will be projected into the slot by the action of the spring 18, and the valve 17 will 90 be opened so that the oil in the spaces 16 between the rod 14 and the face of the opening 12 will flow into the cylinder. This oil will follow the groove 6 in the face of the piston, and since this groove extends completely 95 around the periphery of the piston, the entire surface between the face of the piston and the wall of the cylinder will be lubricated. It will thus be seen that the oil fed to the cylinder will be intermittent and because of this reason there will not be an excess of oil existing between the piston and the wall of the cylinder. However, there will be sufficient oil for lubricating purposes and sufficient oil to act as a seal. The presence 100 of the non-heat conducting plate 2' on the upper end of the piston prevents to a 105

great extent, the heating of the piston by the explosion in the upper chamber, and because of this action the body of the oil, which is between the piston and cylinder, is not 5 broken down and consequently a more perfect lubrication and a longer life of the oil is insured.

It will be seen that when the valve is 10 opened the oil will flow into the chamber which is formed at 13. Of course, at this time part of the oil will pass into the grooves 6 and lubricate the cylinder. When, however, the valve is closed some of the oil will remain in the chamber at 13 and when the 15 valve is again opened that oil will be forced into the groove 6 by the valve as the incoming oil fills the chamber. Thus there will be, in effect, a forced feed.

What I claim is:

20 1. The combination with an internal combustion engine cylinder and piston, which latter is provided with a cam slot in its face, of an oiling device attached to the cylinder and having an oil duct communicating with

the interior thereof, a valve for closing said 25 duct, a cam operable against the face of the piston to maintain said valve closed, and means for projecting the cam into the cam slot to open the valve when the slot is alined with the cam.

2. The combination with an internal combustion engine cylinder and piston, the piston having a peripheral groove therein, and the cylinder having an oil chamber therein, of means for supplying the chamber with 35 oil, and spring actuated means controlled by the movements of the piston for forcing the oil from the chamber into said groove.

3. The combination with an internal combustion engine cylinder and piston, the piston having a peripheral groove therein, and the cylinder having an oil chamber therein, of means for supplying the chamber with oil, and a spring actuated piston controlled 40 by the movements of the piston for forcing the oil from the chamber into said groove.

In testimony whereof I affix my signature.
OWEN J. McGANN.
